UNITED STATES PATENT OFFICE.

JOSEPH F. RUSSELL, OF CHICAGO, ILLINOIS, ASSIGNOR OF ONE-HALF TO MABEL I. ANDERSON, OF CHICAGO, ILLINOIS.

RAIL-FASTENING DEVICE.

1,177,813.

Specification of Letters Patent.

Patented Apr. 4, 1916.

Application filed April 23, 1915. Serial No. 23,392.

To all whom it may concern:

Be it known that I, JOSEPH F. RUSSELL, a citizen of the United States, and a resident of the city of Chicago, county of Cook, and 5 State of Illinois, have invented new and useful Improvements in Rail-Fastening Devices, of which the following is a specification.

My invention relates to improvements in 10 rail fastening devices and has for its object the production of a device of this character which will be of improved construction and efficient in operation.

Other objects will appear hereinafter. 15 The invention consists in the combinations and arrangements of parts hereinafter described and claimed.

The invention will be best understood by reference to the accompanying drawings 20 forming a part of this specification, and in which,

Figure 1 is a top plan view of a rail fastening embodying the invention, showing the same in operative relation with the rail, 25 Fig. 2, a side elevation of the construction shown in Fig. 1, Fig. 3, a section taken on line $x-x$ of Fig. 1, Fig. 4, an end elevation of the construction shown in Fig. 1, and Fig. 5, an enlarged plan view of one of the 30 gripping members embodied in the construction.

The preferred form of construction as illustrated in the drawings comprises a rectangular metallic base plate 1 upon which 35 the rail 2 which it is desired to fasten is adapted to be mounted. The plate 1, in use, is secured to the corresponding supporting tie by means of spikes or pins 3, 4, and 5.

Formed at the upper side of the base 40 plate 1 adjacent one end thereof is a permanent jaw 6 adapted for engagement with one edge portion of the base of the rail. Mounted upon the upper side of the plate 1 at the opposite end thereof is a movable jaw 45 7, secured in position by means of the spikes 4 and 5 which pass through elongated slots formed in the rearward portion 8 of the jaw 7, the elongation of said slots permitting, of course, of the desired shifting 50 movement of the jaw. Formed integral with the jaw 7 is a forwardly projecting tenon 9 which slidably engages an elongated slot 10 formed for the reception thereof in the plate 1. Said tenon, when

the device is in use, is adapted to engage 55 under the base of the rail, as clearly shown in Fig. 3, so that the rail serves as a means of positively locking the jaw 7 against upward movement.

The jaw 7 is locked in operative position 60 by means of a locking member 11 which is pivotally secured in position by means of the pin 5. In order to insure against binding of the head of said pin against the upper side of said member 11 and thus prevent 65 pivotal movement of said member, a bushing 12 is employed which surrounds said pin, said bushing being of such a height as to project slightly above the upper side of the member 11 for engagement with the 70 under side of the head of pin 5 as clearly shown in Fig. 3. With this arrangement it will be seen that the member 11 will be securely fastened in position, but at the same time will be free for pivotal movement in 75 order to permit of the free end thereof being moved into engagement with a shoulder 11' formed for engagement therewith upon the movable jaw portion 8. Pivotal movement of the member 11 in one direction, after said member is in locking position, is prevented by means of a lug 13, movement of said member in the opposite direction being prevented by a spike 14 adapted to be driven into operative position engaging 80 85 the registering slots 15 and 16 formed in the jaw portion 8 and the plate 1.

Mounted at the bottoms of the jaws 6 and 7 are gripping members 17 each of which is provided at its inner edge with oppositely 90 disposed ratchet teeth 18 and 19 adapted for engagement with the corresponding outer edge of the base of the rail in order to positively prevent creeping of the rail. At the ends of the members 17 are provided rearwardly turned stop lugs 20 adapted for engagement against the opposite sides of the jaws 6 and 7, as clearly shown in Fig. 1, to lock the members 17 against longitudinal movement.

With the construction set forth, in the fastening of a rail therein, the jaw 7 is slid outwardly to its outer terminal of movement, the base of the rail being then placed upon the plate 1 and one side of the base thereof engaged with the jaw 6. The jaw member 7 is then slid into engagement with the opposite edge of the rail base and the member 11

turned to engagement with the shoulder 11' in order to lock said jaw in operative position. When the member 11 is in operative position the spike 14 is driven to position to 5 securely hold said locking member in operative relation with the shoulder 11'. With this construction, the rail will be securely clamped between jaws 6 and 7 and positively held against creeping by the gripping members 17. Because of the comparatively large 10 size of the plate 1, considerable purchase for engagement thereof with a wooden tie is afforded which prevents sinking of the same into the tie such as is the case when the rail 15 base is mounted directly upon the tie. The construction is simple and permits of ready mounting or demounting of the rail.

While I have illustrated and described the preferred form of construction for carrying 20 my invention into effect, this is capable of variation and modification without departing from the spirit of the invention. I, therefore, do not wish to be limited to the precise details of construction set forth, but 25 desire to avail myself of such variations and modifications as come within the scope of the appended claims.

Having thus described my invention what I claim as new and desire to secure by Letters Patent is:

1. A rail fastening comprising a base plate upon which the rail is adapted to be mounted; a permanent jaw on said plate for engagement with one edge of the base of 35 the rail; a movable jaw coöperating with said plate for engagement with the opposite edge of the rail base; a pivotally mounted member adapted to be turned into engagement with one edge of said jaw to lock the same in operative position; a permanent stop for holding said member against movement in one direction; and a movable pin 40 for holding the same against movement in the other direction, when said member is

in operative position, substantially as described.

2. A rail fastening comprising a base plate upon which the rail is adapted to be mounted; a permanent jaw on the upper side of said plate for engagement with one 50 edge of the base of the rail; a movable jaw slidably mounted upon the upper side of said plate for engagement with the other edge of the rail base; spikes for fastening said plate to a rail tie, said spikes passing 55 through elongated slots in said movable jaw for fastening the latter to said plate in a manner permitting of relative sliding thereof; and means for locking said movable jaw in locking position, substantially as described.

3. A rail fastening comprising a base plate upon which the rail is adapted to be mounted; a permanent jaw on said plate for engagement with one edge of the base of the 65 rail; a movable jaw coöperating with said plate for engagement with the opposite edge of the rail base; a pivotally mounted member adapted to be turned into engagement with one edge of said jaw to lock the same in 70 operative position; a headed pin passing through an opening in one end of said member for pivotally securing said member in position upon said plate; and a bushing arranged in said opening surrounding said 75 pin, said bushing being of a height slightly greater than the corresponding dimension of said member to prevent binding of the head of said pin upon the upper side of said member, substantially as described.

In testimony whereof I have signed my name to this specification in the presence of two subscribing witnesses.

JOSEPH F. RUSSELL.
